United States Patent Office

Des. 197,140
Patented Dec. 17, 1963

197,140

SHAFT ALIGNER

Donald J. Goguen, Mattapan, and John J. Coleman,
Rockland, Mass., assignors to C. L. Berger & Sons,
Inc., Boston, Mass., a corporation of Massachusetts

Filed June 29, 1962, Ser. No. 70,742

Term of patent 14 years

(Cl. D52—1)

Fig. 1

Fig. 2

Fig. 3

Fig. 4

FIGURE 1 is a view in perspective of a shaft aligner showing our new design.

FIGURE 2 is an enlarged plan view.

FIGURE 3 is an elevational view, enlarged, as seen from the right of FIGURE 1.

FIGURE 4 is a front elevational view as seen from the right of FIGURE 3.

The broken line portion of the disclosure is shown for illustrative purposes only.

We claim:

The ornamental design for a shaft aligner, substantially as shown and described.
